COMBINED EVAPORATOR CASE AND AIR CON-
TROL PANEL FOR AN AUTOMOBILE AIR-
CONDITIONER

Don P. Dixon, 4926 Space Center Drive,
San Antonio, Tex. 78218

Filed Nov. 17, 1972, Ser. No. 307,430

Term of patent 14 years

Int. Cl. D23—04

U.S. Cl. D23—142

FIG. 1 is a perspective view taken from the front and one side of a combined evaporator case and air control panel for an automobile air-conditioner embodying my design; and

FIG. 2 is an inverted perspective view taken from the rear and other side thereof.

The broken lines in FIG. 1 indicating adjacent portions of the windshield, ceiling and side walls of the automobile are shown for illustrative purposes only.

I claim:

The ornamental design for a combined evaporator case and air control panel for an automobile air-conditioner, substantially as shown and described.
